SPECIFICATION forming part of Design No. 11,600, dated January 18, 1880.

Application filed December 10, 1879. Term of patent 3½ years.

To all whom it may concern:

Be it known that I, FRANK H. SHEPHERD, of Boston, in the county of Suffolk and State of Massachusetts, have invented and produced 5 a new and original Design for a Holder for Flowers, Matches, &c., of which the following is a full, clear, and exact description, reference being had to the accompanying photograph, making part of this specification.

10 This invention consists in a design for a holder for flowers, matches, &c., to be used as an ornament for tables, mantel-pieces, &c.

In the photograph, A represents an inverted thimble, which forms a receptacle for holding 15 flowers, matches, &c., the thimble being supported by a pair of open scissors, B, and a pair

of knitting-needles, C, rising from a base, D, made to represent a pin-cushion, a beautiful and unique design being thus produced.

What I claim as my invention, and desire 20 to secure by Letters Patent, is—

The design for a holder for flowers, matches, &c., consisting of the inverted thimble A, supported by the scissors B and needles C, rising from the base D, substantially as herein shown 25 and described.

Witness my hand this 6th day of December, A. D. 1879.
